APPARATUS FOR CLEANING BOTTLES

Arthur S. Hamilton, Jr., Brighton, N. Y.

Application July 11, 1950, Serial No. 173,170

2 Claims. (Cl. 15—60)

1

This invention relates to apparatus for cleaning the exterior surfaces of bottles, having to do particularly with removing paint, coloring matter, dirt, dust, or other substance from the outer surfaces of bottles without permitting access of the cleaning agent to the interior of the bottle, and it has for its purpose to afford an efficient and practical machine for performing these functions expeditiously and thoroughly.

It is a common practice to apply paint or coloring material to the exterior surfaces of bottles for labeling purposes, and in the performance of this operation a large number of bottles are misprinted or defectively labeled, making it necessary to remove the paint or coloring material from the bottle, and it is a particular object of the invention to afford an apparatus of a practical construction which can be operated in an economical manner to effectively remove paint or coloring material from such rejects, so that they can be quickly readied for redecoration or labeling.

Heretofore this has been accomplished usually by hand and the coloring material removed from the surfaces of the bottles by means of wire brushes, in some instances the bottles having been gripped tightly and rotated against brushes, and it is a further purpose of the invention to afford means by which the exterior surfaces of the bottles can be effectively cleaned by sprays of a heated mixture of water and detergent, the sprays of cleaning material being directed against the bottles in such fashion and under such pressure as to strip or thoroughly loosen any paint or coloring material adhering to the surface of the bottle, while preventing the possibility of any cleaning material gaining access to the interior of the bottle.

Another purpose of the invention is to afford a structure that moves a series of bottles, while inverted, continuously in a horizontal plane through a wash chamber where the bottles are subjected to a multiplicity of heated sprays of water and detergent under pressure to loosen the paint or coloring material, thence between a pair of rotary driven brushes that rotate the bottle while in contact therewith and remove the previously loosened coloring material, then through a series of washing sprays, and finally through a rinse chamber in which the exterior surfaces of the bottles are thoroughly rinsed by a multiplicity of sprays of heated water arranged in the same manner as in the wash chamber.

An additional object of the invention is to afford a practical mechanism in which the bottles can

2

be fed through successive wash and rinse chambers located above wash and rinse tanks respectively, into which the washing and rinsing water falls after being sprayed over the bottles as they pass therethrough, while effective means are provided to maintain a constant circulation between the wash and rinse tanks and the spraying devices in the wash and rinse chambers respectively, together with means for effectively heating and controlling the temperature of the water in the wash and rinse tanks.

To these and other ends, the invention consists in the construction and arrangement of parts that will appear clearly from the following description when read in conjunction with the accompanying drawings, the novel features being pointed out in the claims following the specification.

In the drawings:

Fig. 1 is a side elevation of an apparatus constructed in accordance with one embodiment of the invention and operable to carry out the subject matter of the invention;

Fig. 2 is a horizontal plan view with the upper part of the housing removed, and showing the bottle conveyor with the wash and rinse tanks therebeneath;

Fig. 3 is an enlarged detail transverse sectional view through the conveyor and the supporting guide tracks;

Fig. 4 is a plan view with parts broken away of the guideway for the conveyor;

Fig. 5 is an end elevation of the same;

Fig. 6 is a longitudinal vertical sectional view taken centrally of the machine and looking in a direction opposite to that of Fig. 1;

Fig. 7 is a transverse vertical sectional view taken through the wash chamber and wash tank;

Fig. 8 is a transverse vertical sectional view taken through the rinse chamber and rinse tank;

Fig. 9 is a view in end elevation looking toward the inlet end of the machine;

Fig. 10 is a similar view looking toward the outlet end of the machine;

Fig. 11 is an enlarged detail view in elevation of one of the bottle holders;

Fig. 12 is a plan view of the same, and

Fig. 13 is a detail sectional view of one of the brushes.

Referring more particularly to the drawings in which like reference numerals refer to the same parts throughout the several views and to Figs. 2 and 6, the invention in the embodiment illustrated includes a wash chamber designated generally at 1 and a rinse chamber designated at 2, while 3 and 4 designate wash and rinse tanks

55

located beneath the wash and rinse chambers respectively and adapted to receive the wash and rinse waters after they are sprayed on to the bottles, as will be described more fully presently, and from which the wash and rinse waters are returned to the spray devices located in the wash and rinse chambers respectively.

The wash and rinse tanks are separated by a partition 5 and the wash and rinse chambers are separated by a suitable wall 6, and provided at their ends with the walls 7 and 8 respectively, said walls 6, 7 and 8 being provided with openings within which may be located flexible curtains divided at their central portions to permit the bottles to pass therethrough, and acting to prevent water from the wash chamber being sprayed into the rinse chamber and to prevent water from the wash and rinse chambers from being sprayed outside the machine housing, which includes a top wall designated generally at 9 and a bottom wall designated at 11 which may be mounted on suitable bases or supports, while 12, 12 designate drain outlets from the wash and rinse tanks.

The bottles are fed through the machine at a rate varying from sixteen to thirty-six bottles per minute in a horizontal plane on an endless chain 13 which is provided with brackets 14, see Figs. 11 and 12, each bracket carrying an upstanding spindle or post 15 that extends inside a bottle when inverted, while 16 designates a base or support of plastic or other suitable material at the base of the spindle 15, the bottle resting thereon in the position indicated in Fig. 9 when traveling through the machine. The endless chain or conveyor 13 travels between upper and lower tracks or guides 17 and 18, see Figs. 3 and 5, which are supported by side plates 19 and travels on a bottom plate 21 which supports the conveyor tracks and is in turn mounted on plate 22 that is supported by the longitudinally extending right-angular plate 23 fixedly attached theretherein and suitably attached to the cross-members 24, see Figs. 4 and 5, mounted in any convenient fashion on the frame of the machine.

The endless conveyor 13 travels in the direction indicated in Fig. 2 around sprocket wheels 25 and 26, the sprocket wheel 26 being an idler wheel and sprocket wheel 25 being mounted on an arbor 27, see Figs. 1 and 9, which is operated from electric motor 28 to turn the arbor 27 and move the endless conveyor continuously, thus effecting movement of the bottles through the apparatus. The bottles are removed from the spindles or posts 15 by an operator at one end of the machine after they have passed therethrough, additional uncleaned bottles being placed on the spindles at the same time for subsequent cleaning.

As the bottles travel through the machine, they are subjected in the wash chamber to sprays of a heated mixture of water and detergent under pressure, these sprays being arranged so as to strike the exterior surfaces of the bottles at acute angles between horizontal and vertical planes, and to accomplish this there are provided in the wash chamber 1 spray pipes indicated at 29, 31 and 32 respectively on opposite sides of the vertical center along which the bottles travel, and these spray pipes are provided with outlets and spray nozzles arranged at close intervals and directed downwardly at an acute angle between horizontal and vertical planes, as indicated in Fig. 7, so as to strike the outer surface of a bottle at opposite points adjacent to the upper, lower

and central portions of the bottle and at acute angles, causing the hot spray of water and detergent under pressure to loosen any adhering paint or coloring material.

5 The water and detergent when sprayed on to the outer surfaces of the bottles is preferably at a temperature of between approximately 180° F. and 190° F., and the cleaning liquid is maintained at a minimum pressure between approximately twenty-five and thirty-five pounds per square inch at each spray nozzle in the wash chamber. Thus the water is atomized and there is maintained in the wash chamber a mass of water vapor or water particles in suspension that 10 effectively soak the exterior surface of the bottle and any coloring material adhering thereto, and the sprays being directed at approximately the angles shown and under the pressure described above act to strip the paint or coloring material 15 from the bottle in a manner that is not possible with procedures and mechanisms that have heretofore been followed, while at the same time the cold air emerging from each bottle expands and thus prevents moisture from entering and forming 20 on its interior surface. After striking the bottles, the water falls into wash tank 3, from which solid matter that settles in the bottom of the tank may be removed through clean-out doors which may be conveniently arranged. 25

25 The water in wash tank 3 is drawn through pipe 33, connecting with the bottom of the wash tank, see Fig. 1, and pump 34 forces it upwardly through pipe 35 which leads inwardly to the wash chamber 1 and connects with the spray pipes 30 39, 31 and 32 already described, the pump 34 being operated by electric motor 36, it being understood that detergent is placed in the wash tank as required. A continuous circulation of water to the spray devices in the rinse chamber is maintained through pipe 37 which connects with the bottom of the rinse tank by means of pump 38 through pipe 39, see Fig. 1, which enters the rinse chamber 2 and connects with the spray pipes 41, 42 and 43 arranged therein on opposite sides of 35 the path of the bottles and conveyor, at the same angles as already described with reference to the wash chamber, the pump 38 being operated by the electric motor 44, see Fig. 1.

35 The water in the wash and rinse tanks may be 40 retained at the required temperature by steam pipe 45 extending within the wash tank, see Figs. 6 and 7, and steam pipe 46 extending within the rinse tank, see Figs. 6 and 8, the steam pipes being provided with suitable outlet openings within the wash and rinse tanks and connected with any suitable source of steam supply. If preferred, the water in the wash and rinse tanks may be heated by gas burners, connected with any suitable heat-transfer units in the tanks, or the water 45 may be heated by electrical units in heating contact with the sides or interior of the tanks, the particular method of heating the water forming no part of the present invention, and the steam supply may be automatically controlled by suitable temperature-controlled solenoid valves in the steam lines. Fresh supplies of water can be supplied to the wash and rinse tanks in any convenient fashion as by means of hose or otherwise, it being understood that the water in the wash and 50 rinse tanks is heated and continuously circulated to the wash and rinse chambers in the manner already described.

55 The pumps which maintain circulation between the wash tank and spray devices in the wash chamber and the rinse tank and spray de-

vices in the rinse chamber are operated to maintain a pressure at the spray nozzles of approximately twenty-five to thirty-five pounds per square inch in the wash chamber and approximately eighteen to twenty-three pounds per square inch at the spray nozzles in the rinse chamber, at which pressures the paint is successfully soaked and loosened.

It is desirable to afford a means for removing most of the paint, coloring matter or other adhering material on the surface of the bottles before the final washing operation, and in order to accomplish this, there are provided in the wash chamber two vertically disposed rotating brushes indicated at 47 and 48, see Figs. 6 and 7, and mounted on vertical shafts 49 and 51 respectively which are supported in suitable bearings and provided at their upper ends with the gear wheels 52 and 53 between which is located the meshing pinion 54 on shaft 55, that is driven by the electric motor 56 to rotate the gear wheels 52 and 53 in the same direction. The brushes 47 and 48, one of which is shown in detail in Fig. 13, are preferably formed of nylon plastic bristles and when a bottle is moved in between the positively-driven rotating brushes and in contact therewith, the brushes effect a rotation of the latter and effectively remove from the surface of the bottle the paint, coloring matter, or other material previously loosened by the initial washing operation and not already removed in the washing chamber.

The brushes 47 and 48 are located intermediate the ends of the wash chamber so that the bottles are subjected to an additional washing operation from the hot sprays of water and detergent after passing the brushes and after most of the loosened paint or other matter has been removed by the brushes. Thus a final and effective washing takes place to remove any material that may still adhere before the bottles enter the rinse chamber, where they are subjected to the action of sprays of hot clear rinse water from the angularly disposed nozzles in the pipes 41, 42 and 43 through which continuous circulation is maintained from the rinse tank as already described.

It is desirable to effect a final rinsing of the bottles with a fresh supply of clear heated rinse water, and to accomplish this there is provided in the rinse chamber, between the spray pipes 41, 42 and 43 and the outlet from the rinse chamber, a spray head 57, see Fig. 6, which directs a spray downwardly in a vertical direction over each bottle just before it passes from the rinse chamber, the spray head 57 being connected to pipe 58 which is coiled through the rinse chamber as at 59 and connected with any suitable source of clear water supply. Thus there is maintained a continuous supply of water for spray head 57, such water coming from a water main or other source to insure a fresh clear supply, and being heated by passing through coil 59 which is located in the rinse tank. Thus the bottles before emerging from the rinse chamber are thoroughly rinsed with a heated supply of clear water which also insures a continuous supply of fresh water in the rinse tank. The heating coil 59 will heat one-half gallon of clear water per minute from 40° F. to approximately 140° F. to 160° F.

Referring to Figs. 7 and 8, 61 designates an overflow pipe in the rinse tank connected with any suitable outlet for maintaining a predetermined level in the rinse tank while 62 is an overflow pipe in the wash tank that is connected with any suitable outlet. It is desirable in connection

70 75

with the wash tank to prevent overflow of the foam or suds on top of the washing liquid through the outlet that maintains the level of washing liquid and to bring about this result, there is provided a cylindrical housing 63 surrounding, spaced from, and supported on the upper end of pipe 62 and affording an overflow level considerably above the upper end of pipe 62. The housing 63 prevents foam or suds which may rest on top of the body of water from overflowing into the pipe 62, so that the foam resulting from the detergent will not run off until it reaches the upper end of housing 63 where it overflows into openings 64, see Fig. 7, while the body of liquid is permitted to rise between pipe 62 and housing 63 and overflow at the upper end of pipe 62. This enables maintaining the desired level of cleaning liquid without undue waste of the foam or suds which is vital to a proper cleaning operation. 65 designates a plate or baffle above the wash tank that receives water from the wash chamber and deflects it into the wash tank, while 66 designates a similar plate or baffle above the rinse tank that receives water from the rinse chamber and deflects it into the rinse tank. 67 and 68 designate sludge baffles in the wash and rinse tanks respectively for containing and preventing recirculation of the sludge which collects and can be removed at intervals through suitable clean-out doors.

While the invention has been described with reference to the particular construction herein shown, it is not confined to the details illustrated and described, and this application is intended to cover such modifications or departures as may come within the purposes of the improvements and the scope of the following claims.

I claim:

1. Apparatus for cleaning the exterior surfaces of bottles comprising an endless conveyor traveling in a horizontal plane and provided with a series of vertically arranged spindles for holding the bottles inverted, wash and rinse chambers through which the conveyor and bottles travel, a pair of vertically arranged rotary brushes arranged intermediate the ends of the wash chamber and engageable with opposite surfaces of a bottle, means for rotating said brushes in the same direction while engaged with the bottle, spray-discharge nozzles arranged in the wash chamber on opposite sides of the brushes and disposed at acute angles between horizontal and vertical planes acting to direct hot sprays downwardly toward a bottle from opposite points, spray nozzles similarly arranged in the rinse chamber and operating to direct rinsing sprays on to the exterior surface of the bottle from opposite points and at acute angles between horizontal and vertical planes, a wash tank and a rinse tank located beneath the wash and rinse chambers respectively, means for heating the water in the wash and rinse tanks, pumps connected with the wash and rinse tanks respectively acting to maintain a continuous circulation of water under pressure to the spray nozzles in the wash and rinse chambers, and an overflow pipe in the wash chamber including an overflow level for liquid, an overflow level thereabove for foam, and a barrier preventing access of foam to the liquid overflow.

2. Apparatus for cleaning the exterior surfaces of bottles comprising an endless conveyor traveling in a horizontal plane and provided with a series of vertically arranged spindles for holding the bottles inverted, wash and rinse chambers through which the conveyor and bottles travel, a

pair of vertically arranged rotary brushes arranged intermediate the ends of the wash chamber and engageable with opposite surfaces of a bottle, means for rotating said brushes in the same direction while engaged with the bottle, spray-discharge nozzles arranged in the wash chamber on opposite sides of the brushes and disposed at acute angles between horizontal and vertical planes acting to direct hot sprays downwardly toward a bottle from opposite points, spray nozzles similarly arranged in the rinse chamber and operating to direct rinsing sprays on to the exterior surface of the bottle from opposite points and at acute angles between horizontal and vertical planes, a wash tank and a rinse tank located beneath the wash and rinse chambers respectively, means for heating the water in the wash and rinse tanks, pumps connected with the wash and rinse tanks respectively acting to maintain a continuous circulation of water under pressure to the spray nozzles in the wash and rinse chambers respectively, a rinsing spray device located above the path of the conveyor between the aforesaid spray nozzles in the rinse chamber and the outlet from the rinse chamber, and spray device acting to direct rinse water downwardly in a vertical direction on to the bottles just before they emerge from the rinse chamber, a water

supply pipe extending through the rinse tank and connected with said last mentioned spray device, and an overflow pipe in the wash chamber including an overflow level for liquid, an overflow level thereabove for foam, and a barrier preventing access of foam to the liquid overflow.

ARTHUR S. HAMILTON, JR.
